UNITED STATES PATENT OFFICE.

WILLIAM M. TILLER, OF POINT PETER, GEORGIA.

PLOW.

SPECIFICATION forming part of Letters Patent No. 634,777, dated October 10, 1899.

Application filed February 14, 1899. Serial No. 705,513. (No model.)

To all whom it may concern:

Be it known that I, WILLIAM M. TILLER, residing at Point Peter, in the county of Oglethorpe and State of Georgia, have invented 5 certain new and useful Improvements in Plows, of which the following is a specification.

My invention is an improvement in plows; and it consists in certain novel constructions 10 and combinations of parts, as will be herein-after described, and pointed out in the claims.

In the drawings, Figure 1 is a perspective view of a plow provided with my improvement. Fig. 2 is a detail top plan view of the 15 double cross and drag bars. Fig. 3 is a side view thereof, the cross-bar being shown in section; and Fig. 4 is a perspective view of the foot-piece, showing a somewhat different construction from that shown in Figs. 1 and 2.

20 The plow has the beam A and the handles B and the standard C. The standard C has the vertically-elongated slot C', which is preferably formed by making the standard of a bar bent upon itself at C², with its arms so 25 formed lapped on opposite sides of the beam A and secured by the bolts C³. These arms are inwardly bent at C⁴ just below the beam A, thus producing the narrow slot C', in which is adjustably held the securing-bolt for the 30 connecting cross-bar of the foot-piece. This foot-piece comprises the cross-bar D, which is slightly bent at its middle portion D' to properly fit against the standard C and has its portion D' provided with an opening D² 35 for the bolt E, which secures it adjustably to the standard C.

At its ends the cross-bar D is provided with the rearwardly-projected and downwardly curved and returned drag-bars F and F', 40 which are provided at their lower ends with suitably-formed shoes or shovels. It is preferred to make the drag-bar F longer than the bar F', so it will project and operate rearwardly with respect to the drag-bar F'. In 45 securing the drag-bars to the cross-bar D the latter is provided near its ends with the longitudinal slots d, which receive the bolts G, which connect the drag-bars to the connecting-bar D, so such drag-bar can be adjusted 50 laterally as may be desired. To brace and steady the drag-bars in place, they are provided at their front ends with rearwardly-

facing shoulders f, which lap along the front edge of the connecting-bar D and aid the securing-bolts in holding the drag-bars firmly 55 and steadily to the connecting cross-bar.

The connecting cross-bar may be adjusted up or down, as may be desired.

While for purposes of adjustment it may be preferred to make the drag-bars separate 60 from the connecting cross-bar, they may, when desired, be made integral with said cross-bar, as shown in Fig. 4, wherein the drag-bars H are bent rearwardly from the opposite outer end of the connecting cross-bar. 65

The central bent portion of the cross-bar adapts it to the standard and permits the drag-bars to be adjusted to the proper position for use.

The invention is simple, easily adjusted, 70 and the parts can be readily detached for the purpose of repairing or renewing any of same.

Having thus described my invention, what I claim, and desire to secure by Letters Patent, is—

1. The herein-described improvement in plows consisting of the standard composed of a bar bent upon itself at its middle to form the opposite arms which are spaced apart to form a slot, the cross-bar provided at its center with a bent portion to conform to the standard and with an opening for the bolt which secures the bar to the standard, such bar having near its ends the longitudinal slots, the drag-bars provided with shovels 80 and having at their front ends shoulders bearing in front of the cross-bar and having near said ends bolt-holes registering with the longitudinal slot of the cross-bar, the bolts securing the drag-bar to the cross-bar and 85 the bolt by which to secure the cross-bar to the standard substantially as set forth.

2. In a plow substantially as described the combination with a standard of a cross-bar secured thereto and provided at the ends 90 with rearwardly-projecting drag-bars provided with shovels substantially as set forth.

3. A plow comprising a standard, and a cross-bar secured at its middle to the standard and provided at its ends with the rearwardly-projecting drag-bars substantially as 95 set forth.

4. In a plow substantially as described the combination of the cross-bar provided near

its ends with longitudinal slots, the drag-bars provided at their lower ends with the shovels, having their front ends upturned along the front edge of the cross-bar and the bolts securing the drag-bars to the cross-bar and passed through the slots of the cross-bar substantially as set forth.

5. In a plow, a cross-bar provided at its

ends with rearwardly-projected drag-bars having shovels, one of said drag-bars being longer than the other substantially as set forth.

WILLIAM M. TILLER.
